UNITED STATES PATENT OFFICE

WILLIAM J. STRANDWITZ, OF CAMDEN, NEW JERSEY

SUN CAR

Application filed June 9, 1931. Serial No. 543,192.

This invention relates to an individual carriage-like vehicle which may be conveniently referred to as a sun car, the same being adapted to accommodate a person, such as for instance a hospital patient or the like in a comforting and convenient manner for out-of-doors recuperative treatment.

The particular structure utilized for accomplishing the desired result constitutes an innovation in portable vehicles of this classification which, in my judgment is a revelation to convalescents and patients needing or desiring a fascinating form of open air sun ray treatment.

More specifically related, the preferred embodiment of the invention comprises a closure containing a cot, having a frontal dressing compartment, and being open at its top to admit air and luminous heat rays.

Interpreted otherwise, the invention comprises a structure characterized by a vertically elongated front compartment and a horizontally elongated rear compartment, the latter compartment being adapted to accommodate the patient while in a reclining position, the entire car or carriage having the general appearance of a portable tent and embodying detachable non-transparent walls or curtains to provide the desired privacy and to allow the occupant to subject himself to the curative effects of the sun and fresh air.

Other features and accessories constituting advantages in the structure as a whole, will become more readily apparent from the following description and drawings. In the drawings:

Figure 1 is a side elevational view of a complete sun car constructed in accordance with the present invention.

Figure 2 is a top plan view thereof.

Figure 3 is a central longitudinal vertical sectional view.

Figure 4 is a fragmentary perspective view of certain of the details.

Figure 5 is a section on the line 5—5 of Figure 3.

Figure 6 is a detail section showing a snap fastener arrangement.

Figure 7 is a horizontal section taken ap-

proximately on the plane of the line 7—7 of Figure 1.

In detail it will be observed that the structure comprises an open wheel supported frame-work so shaped and constructed as to accommodate the various parts of the complete structure. In making up the frame I have found it expedient and practical to utilize angle irons, the horizontal irons 8 being assembled to form a rectangular bottom frame which accommodates the transporting wheels.

In practice it has been found suitable to provide rigid castors 9 at the front and swivelled castors 10 at the back. Rising from the four corners of the wheel supported frame are uprights 11 secured to the wheel supported frame and reinforced by the cornice web bracket 12.

The numeral 13 designates the cot frame which is also made up from angle irons and the numerals 14 represent intermediate vertical uprights which facilitate dividing of the structure into front and rear portions. The numerals 15 designate additional horizontal angle bars having intersecting longitudinal and transverse wires 16 fastened thereto through the medium of coiled anchoring springs 17 to form a spring adapted to accommodate a mattress or cot 18.

This cot is supported in an elevated plane and aids in defining the bed compartment generally designated by the numeral 19. Supported on the frontal portions of the bars 8 of the base frame are wooden slats 20 forming a platform or floor adjacent to which is a depending apron 21. The floor is located at an appropriate elevation with respect to the bed to facilitate entry and exit and aids in defining the front compartment 22 which is intended to facilitate dressing and undressing. Incidentally, the numerals 23 designates clothes or apparel hooks. The numeral 24 designates a hinged entrance and exit door whose hinges are designated by the numerals 25.

These compartments are enclosed by detachable curtains or canvas walls 26 of appropriate shape and dimensions. The upper and lower edges of the canvas walls are re-

inforced to accommodate attaching and retaining hooks 27 designed to engage over the horizontal flanges of the adjacent angle irons of the frame structure. If desired, certain of the edges of the canvas may be formed with snap fasteners 28 such as indicated in Figure 6 to co-operate with the headed studs on the framework to facilitate detachable mounting of the canvas wall. When the walls 10 are in place, a tent-like enclosure is provided to conceal the occupant.

It will be observed from the description and drawings, so far as the invention has been explained, that the gist of the structure 15 is a simple, economical, mobile tent-like enclosure having front and rear compartments to accommodate the patient, to facilitate dressing and undressing, and to allow the nude body to be exposed to sun rays and 20 fresh air treatments.

The bed or cot is elevated to a suitable point above the floor 20 for convenience of entry or exit as well as for spacing the bed above the ground to permit circulation of air 25 beneath the bed and to avoid dampness.

Referring to Figure 3 it will be observed that I provide a pair of tracks in the form of wires 29, these being stretched tautly in parallelism across the open top of the enclosure. 30 In fact, the wires are securely anchored at the front and adjustably attached to tensioning bolts 30 at the back.

Slidable on the wires is an eye shield 31 which comprises a pair of hanger arms 32 and 35 a swingably mounted anti-glare plate 33. This device 31 may be shifted back and forth on the so-called tracks to permit the plate to be arranged over the head of the occupant and to avoid direct glare of sun rays in the 40 eyes of the patient.

The numeral 34 designates a sliding canopy or shade in the form of a plate having appropriate guides 35 attaching it to the track wires. This can be used as a top for 45 the compartment 21 as a temporary shelter in case of unexpected rain or can be shifted back and forth along the substantially open top of the enclosures. These accessories add to the utility of the complete structure.

50 It is obvious, of course, that in developing the idea further suitable ornate features may be embodied so that the structure will measure up to the demands of critical judgment from a standpoint of appearance. The captivating feature of the invention however, is the idea of having a portable carriage or vehicle with an elevated top, a sheltering and dressing compartment, and substantially open top to admit air and sun rays permitting 55 the body to be exposed to the elements, yet concealing the body from the exterior to provide the desired privacy in treatment.

It is believed unnecessary however, to analyze and report the commercial factors of the 60 novel sun car, for it is evident that it is sus-

ceptible of practical usage by all ages and kinds of persons whether recuperating from illness, or merely desiring to maintain good health from sun and fresh air treatments.

It is thought that the description taken in 70 connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired. 75

I claim:

1. A structure of the class described comprising a portable enclosure embodying front and rear compartments, the rear compartment being substantially open at its top to admit sun rays and being provided with a 80 bed.

2. A structure of the class described comprising a portable enclosure embodying front and rear compartments, the rear compartment being substantially open at its top to admit sun rays and being adapted to accommodate a bed, the confining and concealing walls of said compartment being individually detachable for selective usage. 90

3. In a portable health treatment carriage 95 of the class described, a rectangular bottom frame, supporting wheels attached thereto, rectangular horizontally disposed top frame, and uprights connecting said frames together to provide a support, an elevated occupant 100 support mounted in the structure, detachable canvas walls enclosing said structure and attached to adjacent portions of the frame, a slatted floor attached to the first named frame adjacent the front end thereof, an adjustable 105 closure for the top, and additional detachable canvas side walls for the floor equipped portion of the structure.

4. A portable tent-like patient car of the class described comprising a horizontal bottom frame, supporting wheels therefor, a horizontal top frame, uprights secured to the corner portions of said frames and joining them together, a pair of opposed uprights located between said frames and near the front corner uprights and defining a vertically elongated dressing booth, a spring structure supported horizontally in an elevated position between the upper and lower frames and between the rear corner uprights 110 and said intermediate uprights and defining a reclining compartment, a slatted floor built into the lower portion of the booth, detachable canvas side walls enclosing said booth and reclining compartment, a hinged door 115 for said booth to facilitate entrance and exit, adjustable guide wires mounted in the upper frame, a booth cover plate mounted on the front portions of the wires, a pair of hanger arms adjustably mounted on the rear por- 120

tions of said wires, and a tilttable eye shield plate pivotally suspended between said hanger arms and located in said reclining compartment.

5 5. A sun car of the class described comprising a portable wheel supported frame divided into front and rear compartments, the rear compartment being horizontally elongated, an elevated bottom arranged horizontally in said rear compartment, the front compartment being vertically elongated to facilitate entry, exit, and dressing and undressing, and extending to a point below said bottom.

10 6. A sun car of the class described comprising a portable wheel supported canvas covered frame divided into front and rear compartments, the rear compartment being horizontally elongated and provided with an elevated bottom, the front compartment being vertically elongated and extending from a point below said bottom to the external top of the structure to facilitate entry, exit and dressing and undressing, said rear compartment being open at its top, a horizontally adjustable eye shield mounted for usage in said rear compartment, and a slidable sheltering plate supported in the top portion of said front compartment.

20 30 In testimony whereof I affix my signature.
WILLIAM J. STRANDWITZ.
